E. DUCHESNE

PROCESS OF CUTTING THREADS

Filed Nov. 11, 1924

By

Inventor
Ernest Duchesne

Ernest Duchesne

Attorney

UNITED STATES PATENT OFFICE.

ERNEST DUCHESNE, OF SCHENECTADY, NEW YORK, ASSIGNOR TO LANDIS MACHINE COMPANY, OF WAYNESBORO, PENNSYLVANIA, A CORPORATION OF PENNSYLVANIA.

PROCESS OF CUTTING THREADS.

Application filed November 11, 1924. Serial No. 749,254.

My invention relates to an improved process for cutting tapered threads on stay-bolts and the like and it is an object of the same to render it possible to cut such threads 5 without damaging the body of the bolt. In former practice this has been almost an invariable consequence of any effort to cut tapered threads mechanically due to the fact that when the teeth at one end or side of the 10 chaser are brought into proper operative relation with the beginning of the tapered portion the teeth at the other end or side of the chaser would engage with the body of the bolt and cut into it unless it was made 15 with a body of unduly small size or a thin neck.

Referring to the accompanying drawings which are made a part hereof and on which similar reference characters indicate similar 20 parts,

Figure 1 is an end elevation of a die head carrying hobbed cutters or chasers,

Figure 2, a fragmentary section showing the relation of the chasers to the work,

25 Figure 3, an end elevation of a die head provided with milled cutters or chasers,

Figure 4, a fragmentary section showing the relation of the milled chasers to the work,

30 Figure 5, an end elevation of a die head equipped with tangential chasers of the Landis type, and

Figures 6 and 7, fragmentary sections showing the relation of said chasers to the 35 work, Figure 7 showing a chaser having its back parallel to the teeth, and Figure 6 a chaser the back of which is not parallel to the teeth.

In Figure 1 of the drawings reference 40 character 10 indicates the body of a hobbed cutter having chasers 11 mounted thereon as usual. In Figure 3 the body 13 carries milled chasers 14. In Figure 5 the body 15 carries adjustable tangential chasers 16 45 held in chaser holders 17 as in the well-

known type of Landis thread cutting machines.

In each of Figures 2, 4, 6 and 7 there is shown a stay-bolt having a body 18, a head 19 and a tapered portion 20 on which threads 50 are to be formed. In each instance also the cutters are shown in the position assumed when the cutting has been partly performed, it being the purpose of my invention to begin the cutting at the larger end of the taper 55 and work down to the smaller end. In previous practice it has uniformly been customary to begin at the smaller end and work toward the larger whereby the chaser teeth at the portion *a* (Fig. 2) of the chaser 60 cut into and damage the shank or body of the bolt but by beginning such cutting at the larger end the thread is finished before the tooth *a* reaches the shank of the bolt.

It will be obvious from the illustration 65 that my invention is not limited to any particular type of cutter it being only necessary that the controlling means for the cutters be so arranged as to diminish the size of the opening in the head as the cutting 70 proceeds.

Having thus fully described my said invention, what I claim as new and desire to secure by Letters Patent is:

The process of cutting a thread on the tapered portion of a bolt having a cylindrical shank and a head tapering toward said shank consisting in cutting threads from the larger end toward the cylindrical shank by means of a die head having a set of chasers that 75 approach each other during such cutting operation, and withdrawing the chasers before engagement with the shank can occur, substantially as set forth.

In witness whereof, I have hereunto set 85 my hand at Schenectady, New York, this 17th day of October, A. D. nineteen hundred and twenty-four.

ERNEST DUCHESNE.
